UNITED STATES PATENT OFFICE.

ANDREW ALLAN JOHNSON, OF CHICAGO, ILLINOIS, ASSIGNOR TO DELOS E. WARD, OF CHICAGO, ILLINOIS.

COIN-CONTROLLED CLOCK.

Application filed May 28, 1926. Serial No. 112,198.

My invention relates to a savings device, and particularly to a coin controlled clock of the type wherein the winding and setting of the clock can only be effected upon the insertion of coins in a coin receiving chamber associated with the clock. One object of my device is to provide a practical and pleasing savings device. Another object is to provide a clock associated with the coin savings compartment, it being necessary to make daily or frequent deposits of coins in the compartment in order to wind the clock and keep it going. Other objects will appear from time to time in the course of the specification and claims.

I illustrate my invention more or less diagrammatically in the accompanying drawings, wherein—

- 20 Figure 1 is a front elevation of my clock;
- 20 Figure 2 is a side elevation;
- Figure 3 is an enlarged rear view with the closure of the coin compartment in position;
- 25 Figure 4 is a similar view with the closure partly withdrawn;
- 25 Figure 5 is a similar view, with parts broken away with the closure removed;
- Figure 6 is a section on the line 6—6 of Figure 5;
- 30 Figure 7 is a section on the line 7—7 of Figure 5;
- Figure 8 is a section on the line 8—8 of Figure 4;
- Figure 9 is a section on the line 9—9 of Figure 7;
- 35 Figure 10 is a section on the line 10—10 of Figure 4;
- Figure 11 is a perspective view of the closure;
- 40 Figure 12 is a perspective view of the main coin chamber;
- Figure 13 is a perspective view of another member cooperating to form the coin chamber;
- 45 Figure 14 is a detail of a variant form of spring; and
- Figure 15 is a detail.

Like parts are indicated by like symbols throughout the specification and claims.

A generally indicates a clock housing body and A¹ a clock mechanism housed therewithin. The clock mechanism forms no part of the present invention but it will be realized that it is completely enclosed within

the member A save for the forwardly projecting lens A² and the abutment rim A³. 55 The various parts of the clock mechanism and the frame members therefor are secured by the bolts B the ends of which pass rearwardly through the plate B¹ which takes the place of the usual rear closure plate for 60 clocks of the type herewith used, and which also forms the rear of the coin chamber, and are secured for example by the nuts B². The coin housing may be further secured to the member A, for example by the screws 65 B³, the main coin housing thus forming an effective unit with the clock mechanism.

The main coin housing member, shown 70 for example in Figure 12, consists, beside the rear wall B¹, of the bottom flange C, reduced in width at its ends as at C¹, and the side flanges C², provided with inturned flanges C³ parallel with the wall B¹, and penetrated by coin slots C⁴. C⁵ is a key 75 aperture, the purpose for which will later appear. C⁶ is a lug upturned from the wall B¹ in general alignment with the aperture C⁵ which, in the assembled clock receives the stub shaft C⁷, one end of which is formed as at C⁸ to receive any suitable key passing through the aperture C⁵. The other end is provided with a lever C⁹, the purpose of which will later appear. The back member 80 B¹ is further perforated as at C¹⁰ C¹¹ to permit the passage of the winding shaft C¹² 85 and the setting shaft C¹³ respectively of the clock.

Serving to close the top of the coin closure is the member generally indicated as D, shown in detail in Figure 13. It has a back portion D¹ conforming to and overlying the upper portion of the member B¹, an outwardly projecting flange D² and a flange D³ downwardly depending from the flange D² and parallel with the back portion D¹. The back portion D¹ is perforated as at D⁴ D⁴ through which, when the mechanism is assembled, pass the ends of the lower clock securing bolts B B whereby the member D is held in position in relation to the rest of the coin housing mechanism. It is further apertured as at D⁵ D⁶ in line with the apertures C¹⁰ C¹¹ and the apertures D⁷ D⁸ of the flange D³. It is also slotted as at D¹⁰, and D¹¹ for purposes which will later appear. 100 105

Positioned against the member B¹ is the spring latch housing generally indicated as E and shown in Figure 15. It includes the back portion E¹ and the outwardly projecting flanges E² E³, the upper flange E³ being slotted as at E⁴ to permit the passage of the lever C⁹ of the stub shaft C¹. Positioned within the member E, between the flanges E² E³, is the leaf spring E⁵ having terminal loops E⁶ E⁷ and being centrally secured by the bolt E⁸ which passes through the aperture E⁹ in the bottom portion E¹ and through the aligned aperture E¹⁰ of the member B¹ and through the slot D¹⁰ of the member D. The member E has at one end the lug E¹¹ which projects into the hole E¹² in the plate B¹ to hold the part E from turning. When the mechanism is assembled the flange D³ of the member D partially overlies the loops of the springs, as shown in Figure 5. The slot D¹¹ is provided to permit the part D¹ to pass the lug C⁶ on the part B¹, in assembling.

G generally indicates the closure member, herein shown as including the plane back portion G¹ with the upset portion G² formed therein or secured thereto to facilitate movement thereof. G³ is a bottom flange which abuts against the lower flange C of the member B¹ when the closure is in fully closed position. G⁴ G⁵ are inwardly turned spacing flanges at the upper corners of the closure. G⁶ G⁷ are a plurality of inwardly projecting stop or catch members positioned a short distance below the upper edge of the member G¹, and G⁸ is a single catch positioned even closer to the upper edge, on the side of the closure adjacent the key actuated stub C⁷.

When the device is fully assembled the leaf spring E⁵ is seated in the channel formed by the flanges E² E³ of the member E, and the entire assembly is firmly secured, in the first place by the bolts B, nuts B² and screws B³ and in the second place by the bolt E⁸. The closure is slidably inserted, the spacing flanges G⁴ G⁵ passing through the interval between the edges of the flange C and the side walls C² of the coin closure. The cut away portion C¹ C¹ of the lower flange C permits the passage of the catch members G⁶ G⁷. When the closure is thrust into full closing position, the catches G⁶ each are engaged by one of the spring loops E⁶ E⁷, which serve as spring latches. Either one may be released by the insertion of a coin H through the coin slot C⁴. In the preferred form of my invention, there being a catch or latch engagement at each side of the closure, it is necessary to insert two coins coincidentally in order to obtain the release of the closure. When so released, the closure may be downwardly moved, but the downward movement of the closure moves the releasing coins

downwardly and drops them into the body of the coin container. Accordingly the catch G⁸ engages the loop E⁷ and further withdrawal of the closure is prevented. However, in the exposed space the key controlled shafts C¹² C¹³ are exposed, whereby the clock may be wound or set. By this arrangement the user of the clock is denied access to the winding mechanism and cannot wind or set the clock unless he coincidentally deposits two coins. Even a deposit of the two coins releases the closure only sufficiently to expose the winding and setting mechanism, but the coins within the container are still enclosed. In order to obtain further access to the container it is necessary to rotate the stub C⁷ thus depressing the lever C⁹ and compressing the spring loop E⁷, thereby releasing the catch G⁸ and permitting complete withdrawal of the closure. I may, if desired, have the stub C⁸ shaped identically with the winding and setting stubs C¹² C¹³, or I may differently form it in order that the winding and setting key may be inoperative in order to open the coin container.

Whereas I have described as my preferred form a spring with two loops, it is obvious that an operative device may be produced in which more than two loops or more than two latch members are employed and also wherein a single loop or a single latch member is employed. Figure 14 illustrates a variant form employing a single loop, the structure being otherwise identical as shown in Figure 6.

The coin container is integrally attached to the clock mechanism and cannot be removed therefrom unless the coin closure is fully removed. The ends of two of the bolts B are enclosed within the coin container, as are the screws B², whereby the container is secured to the clock housing body A. The screws which hold the coin container assembly together are all enclosed within the container, and access can be had to them only upon complete removal of the closure.

It will be realized that whereas I have described and shown a practical and operative device, nevertheless many changes might be made in the size, shape, number and disposition of parts without departing from the spirit of my invention. I therefore wish my drawings and description to be taken as in a broad sense illustrative and diagrammatic rather than as limiting me to my specific description and disclosure. In particular, I do not wish to be limited specifically to the use of two loops or two latches, except in so far as certain of the claims may be specifically so limited.

I claim:

1. In a coin controlled clock, a clock mechanism, a coin container associated therewith,

and a closure for such container, a clock control means positioned to be enclosed in said container, locking means for said closure adapted to be released in response to coin insertion, and means for limiting the movement of such closure, after such coin release, to a movement sufficient to expose the clock control means, and insufficient to permit the removal of coins from the container.

2. In a coin controlled clock, a clock mechanism, a coin container associated therewith, and a closure for such container, a clock control means positioned to be enclosed in said container, locking means for said closure adapted to be released in response to coin insertion, and means for limiting the movement of such closure, after such coin release, to a movement sufficient to expose the clock control means, and insufficient to permit the removal of coins from the container, and additional means for further releasing the closure to permit access to the container.

3. In a coin controlled clock, a clock mechanism, a coin container associated therewith and a closure for said container, a clock control means positioned to be enclosed in said container, a lock member for said closure adapted to be moved into release position by coin insertion into the container, a stop member positioned on said closure and adapted normally to be engaged by said lock member, an additional stop member adapted to engage said lock member when the closure has been moved a predetermined distance after release, and additional means for effecting its release from the lock member.

4. In a coin controlled clock, a clock mechanism, a coin container associated therewith and a closure for said container, a clock control means positioned to be enclosed in said container, a lock member for said closure adapted to be moved into release position by the insertion of coins into the container, a stop member positioned on said closure and adapted normally to be engaged by said lock member, an additional stop member adapted to engage said lock member when the closure has been moved a predetermined distance after release, and additional means for effecting its release from the lock member, comprising in part a key operated shaft and a lock engaging lever positioned thereupon.

5. In a coin controlled clock, a clock mechanism, a coin container associated therewith, a slidable closure for said container, a clock control means adapted to be masked by said closure, a spring latch for said closure and a stop on said closure adapted normally to engage said latch, said latch being adapted to be released from contact with said stop by coin insertion into the container, an ad-

ditional member upon said closure adapted to engage such spring latch when the closure has been moved a predetermined distance after the release of the first stop, and additional means for effecting its release from the latch.

6. In a coin controlled clock, a clock mechanism, a coin container associated therewith, a slidable closure for said container, a clock control means adapted to be masked by said closure, a spring latch for said closure and a stop on said closure adapted normally to engage said latch, said latch being adapted to be released from contact with said stop by coin insertion into the container, an additional member upon said closure adapted to engage such spring latch when the closure has been moved a predetermined distance after the release of the first stop, and additional means for effecting its release from the latch, said spring latch including a leaf spring loop.

7. In a coin controlled clock, a clock mechanism, a coin container associated therewith, a slidable closure for said container, a clock control means adapted to be masked by said closure, a spring latch for said closure and a stop on said closure adapted normally to engage said latch, said latch being adapted to be released from contact with said stop by coin insertion into the container, an additional member upon said closure adapted to engage such spring latch when the closure has been moved a predetermined distance after the release of the first stop, and additional means for effecting its release from the latch, said spring latch comprising a leaf spring loop, the wall of the container being penetrated by a coin aperture positioned adjacent a free loop end.

8. In a coin controlled clock, a clock mechanism, a coin container associated therewith, a closure therefor, a plurality of stops on said closure, a spring latch adapted normally to engage said stops and adapted to be withdrawn from contact with said stops in response to the insertion of coins into the container.

9. In a coin controlled clock, a clock mechanism, a coin container associated therewith, a closure therefor, a plurality of stops on said closure, a spring latch adapted normally simultaneously to engage said stops and adapted to be withdrawn from contact with said stops in response to the insertion of a plurality of coins.

10. In a coin controlled clock, a clock mechanism, a coin container associated therewith, a closure therefor, a plurality of stops on said closure, a spring latch adapted normally simultaneously to engage said stops and adapted to be withdrawn from contact with said stops in response to the insertion of a plurality of coins, said latch comprising a double loop spring, the wall of the

container being penetrated by coin apertures positioned adjacent the free ends of the loops.

11. In a coin controlled clock, a clock mechanism, a coin container associated therewith, a closure therefor, a plurality of stops on said closure, a spring latch adapted normally simultaneously to engage said stops and adapted to be withdrawn from contact with said stops in response to the insertion of a plurality of coins, said latch comprising a double loop spring, the wall of the container being penetrated by coin apertures positioned adjacent the free ends of the loops, and additional means for withdrawing one of said loops in release position.

12. In a coin controlled clock, a clock mechanism, a coin container associated therewith, a closure therefor, a plurality of stops on said closure, a spring latch adapted normally simultaneously to engage said stops and adapted to be withdrawn from contact with said stops in response to the simultaneous insertion of a plurality of coins, said latch comprising a double loop spring, the wall of the container being penetrated by coin apertures positioned adjacent the free ends of the loops, and additional means for withdrawing said loops into release position.

13. In a coin controlled clock, a clock mechanism, a coin container associated therewith, a closure therefor, a plurality of stops on said closure, a spring latch adapted normally simultaneously to engage said stops and adapted to be withdrawn from contact with said stops in response to the insertion of a plurality of coins, said latch comprising a double loop spring, the wall of the container being penetrated by coin apertures positioned adjacent the free ends of the loops, and additional means for withdrawing one of said loops into release position, comprising an overlying key-actuated lever.

14. The combination with a clock of a coin container, a closure for said container, and clock controlling means adapted to be masked by said closure.

15. The combination with a clock of a coin container, a closure for said container, and clock controlling means adapted to be masked by said closure, and means for releasing said closure in response to the insertion of coins into said container.

16. The combination with a clock of a coin container, a closure for said container, and clock controlling means adapted to be masked by said closure, and means adapted to permit the partial release of said closure, in response to the insertion of coins into the container, to permit access to the clock control means.

17. The combination with a clock of a coin container, a closure for said container, and clock controlling means adapted to be

masked by said closure, and means for releasing said closure in response to the insertion of coins into said container, said closure being adapted when open to depend beneath the bottom of the clock base.

70

18. The combination with a clock of a coin container, a closure for said container, and clock controlled means adapted to be masked by said closure, and means for releasing said closure in response to the insertion of coins into said container, said closure being adapted to be returned to closed position in response to the positioning of the clock in upright position upon a supporting surface.

80

19. In a coin controlled clock, a clock mechanism, a coin container associated therewith and a closure for such container, a clock control means positioned to be enclosed by said closure, and a plurality of successively effective locking means for said closure, one being adapted to be released in response to coin insertion into said container, and another being effective after the release of the first.

90

20. In a coin controlled clock, a clock mechanism, a coin container associated therewith and a closure for such container, a clock control means positioned to be enclosed by said closure, and a plurality of successively effective locking means for said closure, one being adapted to be released in response to coin insertion into said container, and another being effective after the release of the first, and release means therefor, including a key operated lever.

95

21. In a coin controlled clock, a clock mechanism, a coin container associated therewith and a closure for such container, a clock control means positioned to be enclosed by said closure, and a plurality of successively effective locking means for said closure, one being adapted to be released in response to coin insertion into said container, and another being effective after the release of the first, and release means therefor, including a key operated lever, access to said lever being masked by said closure when in normal closing position.

105

22. In a coin controlled clock, a clock mechanism, a housing for said mechanism, a coin container associated with said housing, and a closure for said container, means for securing clock housing and container together, said means positioned to be enclosed by said closure, and locking means for said closure, adapted to be released in response to coin insertion into said container.

110

23. In a coin controlled clock, a clock mechanism, a coin container associated therewith and a closure for such container, a clock winding means positioned to be enclosed by said closure, and locking means for said closure, adapted to be released in response to coin insertion into said container.

125

130

24. In a coin controlled clock, a clock mechanism, a coin container associated therewith and a closure for such container, clock winding and setting means positioned to be enclosed by said closure, and locking means for said closure, adapted to be released in response to coin insertion into said container.

25. In a coin controlled clock, a clock mechanism, a coin container associated therewith, said container being formed to permit the simultaneous insertion of a plurality of coins, a closure for said container, locking means for said closure, and means for releasing it in response to the substantially

simultaneous insertion of a plurality of 15 coins.

26. In a coin controlled clock, a clock mechanism, a coin container associated therewith, said container being formed to permit the simultaneous insertion of a plurality of 20 coins, a closure for said container, a locking means for said closure in locking engagement with said closure adjacent the point of insertion of said coins and adapted to be disengaged by their insertion.

Signed at Chicago, county of Cook and State of Illinois, this 24th day of May, 1926.

ANDREW ALLAN JOHNSON.
